REGISTERING APPARATUS FOR MACHINES

Woodford A. Kennedy, Charlotte, N. C.

Application August 6, 1934, Serial No. 738,701

1 Claim. (Cl. 235—125)

This invention relates to a pick counter and more especially to a pick counter having a pre-printed tape therein with figures thereon to denote the number of picks made by a loom, said tape being adapted to be fed from the pick counter in timed relation to the speed of the loom. In keeping check on the amount of goods woven on a loom and also for payroll purposes, a pick counter is often used. The conventional type 10 employs a figure wheel somewhat on the style of an odometer while the individual types are divided into a non-reset, re-setting and to a limited extent printing pick counters. These counters are made for single shifts and also into two 15 shifts or more.

It is a well known fact that when the counters used are of the odometer type, that the reading for each day's work has to be taken by an individual and transferred to a piece of paper denoting the shift, the loom number and the number of picks which have been made by the loom that day in order that the loom operator may be properly paid. This, of course, also results in errors which means that the operator will not be paid 20 properly. In printing counters heretofore used, it has been necessary to mount a printing mechanism in the counter which often is ineffective on account of the fact that the ink dries out or that the stamp becomes gummed up, resulting in 25 faint lines and obscure figures.

It is, therefore, an object of this invention to use a pre-printed roll of paper, tape and the like, and feed the same by means of a directly connected feed roll in direct ratio to the production 30 being made on the loom. The pre-printed tape will be so scaled that a definite space on the tape will represent a unit of measurement of goods produced which ordinarily will be represented by each one thousand picks. If desired, however, 35 the scale on the tape could be changed so that the loom production could be shown in inches, feet, yards or the like.

It is a further object of this invention to provide a pick counter with a plurality of pre-printed 40 perforated tapes therein which are held firmly in contact with the feed rolls by pressure rolls and when these tapes are torn off at the bottom of the apparatus the highest reading noted thereon will denote the number of picks made in a day's work 45 by the loom, or in any given period.

It is still a further object of this invention to provide a pick counter whose feed rolls are held in fixed position at all times by means of a spring locking device. This prevents unauthorized manipulation or tampering with the counter, since 50

by means of this locking device the feed rolls can only be rotated when the drive gears are in their proper position, that is, when the mechanism is connected to the day counter, the night counter is positively locked and conversely, when the 5 counter is shifted to night, the day feed roll is positively locked except when the cover is unlocked and lifted upwardly. In this position the locking mechanism is released and the feed rolls may be turned at will by means of a knurled nut 10 inside the case.

As a further means of preventing unauthorized tampering with the counter, the front cover is so locked that a key is required to open same, and when the key is inserted in the lock it manipulates 15 a suitable marking device such as a pin plunger which will perforate or mark the tape in such a manner as to show that the counter face has been opened.

It is evident that a pre-printed card, sheet of 20 paper, or any other material, may be fed through this apparatus by making minor changes, thus eliminating the rolls of tape.

Some of the objects of the invention having been stated, other objects will appear as the description proceeds when taken in connection with the accompanying drawings, in which:—

Figure 1 is a front elevation of my pick counter;

Figure 2 is a front elevation with portions of the front cover removed showing the mechanism on 30 the interior thereof;

Figure 3 is a sectional view taken along line 3—3 in Figure 2;

Figure 4 is a sectional plan view taken along the line 4—4 in Figure 2;

Figure 5 is a sectional plan view taken along the line 5—5 in Figure 2;

Figure 6 is a sectional plan view taken along line 6—6 in Figure 4;

Figure 7 is a sectional plan view taken along line 7—7 in Figure 5;

Figure 8 is a view of the key adapted to unlock the lock shown in Figures 5 and 7;

Figure 9 is a view of a pre-printed tape which is adapted to be used in this pick counter.

Referring more specifically to the drawings, the numeral 10 denotes a casing on a pick counter which is comprised of a suitable base member 11, sidewalls 12 and 13 and a back wall 14. The back wall 14 has secured thereto a conventional bracket 15, said bracket being secured by any suitable means such as bolts or rivets to the frame 16 of a loom. A front cover 17 is hingedly secured as at 18 to back wall 14, and the lower edge of this cover has a lock therein which will later be de- 55

scribed, and is adapted to lock the cover in fixed position.

Secured to back wall 14 is a receptacle 22 for receiving a pre-printed tape as it is fed from the apparatus and this receptacle is secured to the back wall by any suitable means such as hinges 23. A similar receptacle 20 is hingedly secured to back wall 14 by any suitable means such as hinges 21. The receptacle 20 is adapted, in the present instance, to receive the tape from the day shift whereas, the receptacle 22 receives the tape for the night shift. Receptacles 20 and 22 have suitable latches 24 and 25 respectively, which normally hold the receptacles in a locked position.

Back wall 14 has integral therewith lugs 31 and 32 between which is mounted a worm 33, said worm being fixedly secured on drive shaft 34. Drive shaft 34 is driven in a conventional manner by means of a gear drive from one of the loom shafts.

Worm 33 is adapted to mesh with a worm gear 35 which is slidably keyed on shaft 36, shaft 36 being rotatably mounted in bearings 37, 38, 39 and 40. The gear 35 also has a projection 41 integral therewith which fits in a key-way 42 cut in shaft 36. This allows worm gear 35 to remain stationary when the shaft 36 is moved transversely in the counter but the key-way 42 and projection 41 prevent relative rotation between worm gear 35 and shaft 36.

A U-shaped bracket 43 is secured to the base portion 11 and has its upwardly projecting arms disposed on opposite sides of worm gear 35. This will hold the worm gear 35 in one position when the shaft 36 is moved in the casing and causes this worm gear 35 to mesh with worm 33 at all times.

Pinions 44 and 45 are fixedly secured on shaft 36 and these pinions are adapted to drive a feed roll mechanism which will later be described.

Grooved wheels 46 and 47 are also fixedly secured on shaft 36, said wheels 46 and 47 being engaged by suitable balls 48 and 49 respectively, which form a part of the transferring mechanism. Balls 48 and 49 are mounted on the ends of forked member 50 which is pivotally mounted as at 51 to a bracket 52. This bracket is secured to base member 11 by any suitable means such as screws 53.

A shaft 61 has one end rotatably mounted in bracket 52 and the other end rotatably mounted in sidewall 12. Fixedly secured on shaft 61 is a roller 63 having projections 64 thereon which are adapted to penetrate the perforations 65 in the tape and to feed the tape through the apparatus. Knurled nut 66 is fixedly mounted on shaft 61 which allows one to turn shaft 61 when the counter cover is removed to place the tape in a desired starting position. A pinion 67 is also mounted on shaft 61, said pinion 67 having spaced projections 68 extending from one side thereof. Shaft 69, which is similar in all respects to shaft 61, has one end rotatably mounted in sidewall 13. Fixedly secured on this shaft is roller 70 having projections 71 integral therewith, said projections 71 being adapted to penetrate perforations 65 in the tape.

It is seen that rollers 21 and 28 are rotatably and slidably mounted on shaft 36, said rollers being confined between bearings 37, 38, 39 and 40 respectively. These rolls press the tape against rolls 63 and 70 at all times to insure that projections 64 and 71 will enter perforations 65 in the tapes. A knurled nut 72 is also fixedly secured on this shaft and is identical in all respects to

nut 66 which has already been described. Fixedly secured on the end of the shaft is a pinion 74 having projections 75 projecting from one side thereof and adapted to be engaged by prong 76 when it is desired that the pinion 74 be secured against rotation. A similar prong 77 is adapted to engage the projections 68 on pinion 67 when this pinion is desired to be locked in position. The prongs 76 and 77 project upwardly and then laterally and are secured as at 78 to the front cover 17.

The forked member 50 has projections 86 and 87 extending therefrom which are adapted to engage the downwardly extending prongs 76 and 77 when it is desired that one particular side be operated.

Member 59 has a socket 88 in the front side thereof which is adapted to be engaged by a projection 89, said projection 89 being fixedly secured on the end of a suitable spring 90. The other end of spring 90 is fixedly secured to lever 91 which is pivotally mounted between lugs 92 and 93 by any suitable means such as pin 94. A compression spring 95 is confined around pin 94 and has its upper end engaging the lower side of 94 and its lower end engaging the top side of lever 91. The lower side of lever 91 has integral therewith a projection 96, whereas the lug 93 has cavities or detents 97, 98 and 99 therein spaced on an arc of a circle whose center is pin 94, and are adapted to receive the projection 96 at various positions of lever 91 and to hold the lever in a fixed position.

In Figure 4 the gear 44 is shown meshing with the gear 67, but it is evident should the lever 94 be caused to rotate in a counter-clockwise direction that the member 50 would be caused to rotate in a clockwise direction thereby causing the balls 48 and 49, which are engaging the wheels 46 and 47 respectively, to slide the shaft 36 and the gears 44 and 45 thereon to a different position and when it is shifted far enough to the right, the gear 45 will mesh with the gear 74.

It is to be noted in Figure 4, that the prong 77 is not engaged by the projection 68 on the side of gear 67, and the gear wheel 67 is free to be turned by the gear 44 which is fixedly mounted on shaft 36. In a like manner, when member 50 has been rotated, in a clockwise direction, enough to cause gear 45 to mesh with gear 74, the arm 86 will engage the prong 76 and hold it out of engagement with projections 75 on the side of gear wheel 74, thereby allowing gear 45 to rotate gear 74 and the shaft 69.

In the position of member 50, as shown in Figure 4, the projection 96 on the bottom of lever 91 is engaging the socket 99 in the top of lug 93. If member 50 is turned in a clockwise direction until gear 45 is engaging gear 74, the projection 96 will engage the socket 97 in member 93. When lever 91 is turned to a half-way position between socket 97 and socket 99, the projection 96 will engage the central socket 98 thereby causing the gears 44 and 45 to be disposed between the gears 67 and 74 where neither will mesh with gear 67 or 74. In this position prongs 86 and 87 on member 50, will not engage either of the prongs 76 or 77, therefore it is seen that the apparatus is in neutral position, and both of the gears 67 and 74 are secured against rotation, since prong 77 is engaging projections 75. The spring 90 is provided so that should the apparatus be in neutral position, and it is desired to shift lever 91, so that gears 44 and 67 mesh, if a tooth in gear 44 should strike

the tooth in gear 67, and prevent the gears from meshing with each other, the lever 91 would be pushed all the way so that the projection 96 would engage the socket 99 as shown in Figure 4. It is evident that the spring 90 would be distorted and the member 50 would not be rotated until the drive shaft had rotated the shaft 36 a sufficient amount to cause the teeth in gears 44 and 67 to mesh. When this is done, the tension produced by spring 90 would cause the parts to assume the position as shown in Figure 4.

It is evident that if the teeth in the gear 45 should strike the teeth in the gear 74 that the spring would likewise be distorted in the opposite direction and member 91 could be rotated in a counter-clockwise direction until the projection 96 would engage the socket 97. When the shaft 36 has rotated a sufficient amount to cause the gears to mesh then the tension of the spring 90 would rotate the member 50 in a clockwise direction until the gears were disposed at their proper position.

Sidewall 13 has secured thereto a bolt 100 which has threadedly secured on the end thereof knurled nut 101, said nut 101 being adapted to confine a roll of tape 102 thereon. A similar bolt 103 is also secured in sidewall 13 and has a knurled nut 104 threadably secured on the end thereof which nut confines a roll of tape 105 thereon. Disposed above roll 102 is a tension roller 106 which is rotatably mounted on the left-hand end of member 107, said member 107 being hingedly secured as at 108 to the back wall 14. A similar tension roller 110 is rotatably mounted on the left-hand end of member 111 which is hingedly secured as at 114 to backwall 14.

Sidewall 12 likewise has a pin 121 secured thereto which has a knurled nut 122 on the end thereof confining a roll of paper on the pin. Disposed above this roller is a tension roller 123 which is similar in all respect to roller 106 just described, and is hingedly secured to the backwall 14. Disposed below the bolt 121 is a bolt 119 having a knurled nut 124 threadably secured on the end thereof which confines a roll of tape on the bolt 119. This roller and its associated parts are identical to the rollers which have been previously described. Bolts 126 and 127 are secured on sidewalls 12 and 13 and have rollers 129 and 130a rotatably mounted thereon. These guide the tape as it is being pulled through the apparatus by the rollers 63 and 70. Two rolls of tape are provided in order that a duplicate may be had while it is evident that more rolls may be placed within the casing if it is desired.

It is seen by referring to Figures 2 and 9 that tape 130 has two sets of readings thereon. The scale of graduations 131 on the left-hand side of the tape are the ones which denote the number of picks made by the loom and where this is torn off at the lower edge of the projection 133 it will denote the number of picks which are made during the day. The graduations 135 on the right-hand side of the tape are used merely to denote the number of picks which have been made any time during the day and these graduations are visible through suitable windows 136 and 137 which are cut in the cover 17. It is seen that the reading which is visible through the windows 136 and 137 corresponds to the reading which is at the lower edge of projection 133.

In other words, in Figure 2, if the tape were torn off in this position the reading on the scale 131 would be "20" which would denote 20,000 picks. The reading on the right-hand scale 135

would also be "20" which is visible at this time through the window 136. This affords means for telling the exact number of picks which have been made at any time during the day without opening one of the covers 20 or 22.

In a like manner the paper or tape from the rolls 102 and 105 are moved around the pin 130a and over the roller 70, said roller 70 being adapted to feed the tape downwardly through a suitable slot in the bottom of member 11. The lower side 10 of member 11 is provided with a projection 140 which is identical in all respects to projection 133, and the lower edge of this projection has a knife edge on the front side thereof being adapted to form a guide for tearing the tape when it 15 is desired to remove the tape from the container 22.

Base member 11 has projections 141 and 142 integral with the upper side thereof and these projections have slots in the central portion thereof through which the tape is fed downwardly into the receptacles 20 and 22. A bore 143 and 144 is disposed directly through the central portion of member 141 and 142 and the front edges of these bores are penetrated by suitable pins 145 and 146, 25 said pins being fixedly secured to a bar 147. The bar 147 is secured at its central portion to a pin 148 (Figs. 2 and 7) which projects on the inside of lock 149 and has a button 150 on the end thereof. A suitable compression spring 151 is 30 confined on pin 140 by means of the button 150 and the end wall of lock 149 which normally pushes the pin and the bar to the left in Figure 7.

The lock 149 has a conventional barrel 152 which is adapted to receive a suitable key 153 35 which has a projection 154 on the end thereof which is adapted to contact the button 150 when inserted within the lock. It is seen that when the key 153 has entered the barrel 152, so that it will properly engage the lock to unlock the front 40 wall 17 that the button 150 will be pushed to the right along with the bar 147. This movement to the right will cause the pins 145 and 146 to move inwardly in bores 143 and 144 and to punch the tape which projects down through the slots in members 141 and 142. By this arrangement it is seen that each time the lock 149 is operated, the tape will be punched thereby preventing unauthorized persons from tampering with the counter and insuring that each time the 45 door is opened that a record will be made on the tape.

The barrel 152 has integral therewith projection 152a which is adapted to engage a slot 155 in the base 11, when the cover is in locked position but when the key 153 rotates the barrel 152 to unlocked position the projection 152a will not engage the cavity 155 and the lid may be opened. In order to insure that the bar 147 will remain horizontal at all times, suitable pins 156 60 and 157 are secured in the front wall 17 and slidably penetrate bar 147. When the key 153 has been removed from the lock, the parts 145, 146 and 147 will assume the position as shown in Figures 5 and 7 because the tension spring 151 65 will force the button 150 and pin 148 to the left in Figure 7. While the present showing of the counter is described in conjunction with a loom it is to be understood that the counter may be used as a counting device on other machines 70 such as spinning frames, inspection tables or in fact, on any other device where a counter is desired.

By observing Figure 9 it is seen that the tape is made with a plurality of sections having iden- 75

tical printed graduations thereon. Each set of graduations represents slightly more than a work period's capacity which is shown as 390,000 picks. Let us assume that the capacity is 350,000 picks. This means that immediately before the beginning of a work period the supervisor would unlock the casing and advance the tape to the next zero mark, and when he again locked the casing the tape would be perforated by the plunger 146. When the work period was over unlocking 10 of the casing to set the tape for the next work period would again perforate the tape. Therefore, if any operation produced a tape which was 15 perforated, it would show that some unauthorized person and tampered with the counter. This locking and perforating feature insures accurate recording.

In the drawings and specification there has 20 been set forth a preferred embodiment of the invention, and although specific terms are employed, they are used in a generic and descriptive sense only, and not for purposes of limitation, the scope of the invention being set forth in the accompanying claim.

25 I claim:

A counter comprising a casing, a roll carrying

a plurality of layers of printed tape mounted in the casing, each of said tapes having two offset rows of evenly spaced numbers printed thereon, and the marginal edges of the tapes being perforated, a feed roll mounted in the casing 5 and having teeth projecting therefrom to engage the perforations in the tapes for feeding the same from the roll to the exterior of the casing, a slot in the casing through which the tape is expelled by movement of the feed roll, a driven 10 shaft extending into the casing, a driving connection between the shaft and the feed roll, said casing having a window therein through which one of the rows of graduated numbers on the tape nearest the window is visible, the distance between the window and the exterior edge of the slot in the casing through which the tapes are 15 expelled being such that the reading on one scale of evenly spaced numbers at the exterior of the slot is identical to the reading on the 20 scale visible through the window, so that when the tapes are torn off at the exterior edge of the slot the last number appearing in one column will be identical to the number visible through the window.

25 WOODFORD A. KENNEDY.
